UNITED STATES PATENT OFFICE.

CLEOPHAS GAMACHE, OF BARRE, VERMONT.

AUTOMATIC DOOR OPENING AND CLOSING DEVICE.

No. 826,325.

Specification of Letters Patent.

Patented July 17, 1906.

Application filed March 19, 1906. Serial No. 306,794.

To all whom it may concern:

Be it known that I, CLEOPHAS GAMACHE, a subject of the King of Great Britain, and a resident of Barre, in the county of Washington and State of Vermont, have invented a new and Improved Automatic Door Opening and Closing Device, of which the following is a full, clear, and exact description.

The object of the invention is to provide a new and improved automatic door opening and closing device controlled by a person walking upon a movable platform arranged adjacent to the door, the platform stepped on by the person being pressed down to start a motor connected with one side of the door to draw the latter to open position, the platform when released by the person causing the motor to stop running and allowing a spring or weight to draw the door to closed position.

The invention consists of novel features and parts and combinations of the same, which will be more fully described herein-after and then pointed out in the claims.

A practical embodiment of the invention is represented in the accompanying drawings, forming a part of this specification, in which similar characters of reference indicate corresponding parts in all the views.

Figure 1 is a side elevation of the improvement as applied, the door being in a closed position and parts being broken out and parts being shown in section. Fig. 2 is a like view of the same, showing the door open. Fig. 3 is a transverse section of the same on the line 3-3 of Fig. 1. Fig. 4 is an enlarged cross-section of the door-hanger, the section being on the line 4-4 of Fig. 5. Fig. 5 is a side elevation of the same; and Fig. 6 is a cross-section of the door and door-casing, showing friction guide-rollers for the lower end of the door.

A door A for closing an opening in a wall B of a building is provided at its upper end with a door-hanger C of any approved construction, preferably one having ball-bearings, to allow an easy sliding of the door—that is, for the door to move into an open or a closed position. On one side of the door A is secured a bracket A', in which is journaled a sprocket-wheel D, connected by a sprocket-chain D' with sprocket-wheel D², secured on the shaft of a motor E, attached to the wall B a distance to one side of the door A, as plainly indicated in Figs. 1 and 2. On the sprocket-wheel D is secured a brake-wheel F, engaged

at its peripheral face by a brake-shoe F', held on the free end of a spring F², attached to the door A, (see Fig. 1,) the said brake-shoe F' and brake-wheel F normally holding the sprocket-wheel D against turning the time the door A moves from a closed into an open position. When the door A is in a closed position, as shown in Fig. 1, and the motor E is started, then the sprocket-chain D' is driven, and as it passes over the sprocket-wheel D, held stationary for the time being, it is evident that a pull is insured on the said sprocket-wheel D by the sprocket-chain D', and consequently the door A is drawn into an open position. (See Fig. 2.) When the door A reaches an open position, if the motor E is still running the sprocket-wheel D is turned, as the power of the motor overcomes the action of the brake-shoe F' on the brake-wheel F.

The starting and stopping mechanism of the motor E is controlled by a platform G, arranged underneath the door A and extending a suitable distance beyond it, as will be readily understood by reference to Fig. 3, and the said platform G is mounted at its under side on springs G', resting on the top of a recessed portion B' of the floor of the building, said platform G being guided in its upward and downward movement by suitable guideways G².

In order to control the starting and stopping mechanism of the motor E from the platform G, the following arrangement is made, it being understood that the motor shown in the drawings is an electric motor, and the circuit-wires E' and E² of this motor are connected with contact-plates G³ and G⁴, of which the contact-plates G³ are secured to the under side of the platform G and the contact-plates G⁴ are fixed on the building and are normally out of contact with the contact-plates G³, as the springs G' normally hold the platform G in an uppermost position. Now when a person steps on the platform G the latter is pressed downward by the weight of the person, and consequently the contact-plates G³ move into engagement with the contact-plates G⁴ to close the circuit for the electric motor E, and thereby start the motor. As soon as this takes place the door A is drawn open by the action of the sprocket-wheel and chain connection D D' D² above described. The person on the platform G can now step through the open doorway, and as soon as the person leaves the platform

then the springs G' return the platform to a normal position, whereby the contact-plates G^3 move out of contact with the contact-plates G^4 , and consequently the motor-circuit is opened and the motor stops running.

In order to return the door A—that is, to move it back into a closed position—a coil-spring H is provided, held in a suitable casing H' and connected by a chain or a like flexible connection H² with the door A at or near its upper end, as plainly illustrated in Figs. 1 and 2. The casing H' is attached to the wall B, and the tension of the spring H can be regulated by a suitable crank-arm H³, as shown in Figs. 1 and 2. When the door A is moved into an open position, as above described, the spring H is put under heavy tension, and as soon as the person steps off the platform G and the motor stops running then the spring H draws the door A to closed position.

In order to limit the opening movement of the door A, suitable spring-pressed stops I are provided, arranged on the wall B, and similar stops I' limit the closing movement of the door A.

Roller-guides J, held on the wall B, engage opposite faces of the door A at or near the lower end thereof to insure a proper sliding of the door into an open or a closed position.

Although I have shown and described an electric motor, it is evident I do not limit myself to such a motor, as other motors may be employed for the same purpose, it being, however, understood that the starting and stopping mechanism of the motor is controlled by the movable platform G.

Having thus described my invention, I claim as new and desire to secure by Letters Patent—

1. An automatic door opening and closing device, comprising a motor for moving the door in one direction, a coil-spring held in a casing and having a flexible connection with the door for moving the door in an opposite direction, and a movable platform adjacent to the door and controlling the starting and stopping mechanism of the said motor.

2. An automatic door opening and closing device, comprising a motor, a device on the door mounted to turn, a connection between the motor and said device for exerting a pull on said device to move the door into an open position, means for preventing said device from turning while the door is moving into an open position, a movable platform adjacent to the door and controlling the starting and stopping mechanism of the motor, and means for closing the door on releasing the platform.

3. An automatic door opening and closing device, comprising a motor, a sprocket-wheel and chain connection between the motor and one side of the door, a brake for the sprocket-wheel on the door, and a platform adjacent

to the door and controlling the starting and stopping mechanism of the said motor.

4. An automatic door opening and closing device, comprising a motor, a sprocket-wheel and chain connection between the motor and one side of the door, a brake for the sprocket-wheel on the door, a platform adjacent to the door and controlling the starting and stopping mechanism of the said motor, a spring connected with the opposite side of the door, and means for regulating the tension of the said spring.

5. An automatic door opening and closing device, comprising an electric motor, a device on the door mounted to turn, a connection between the motor and said device for exerting a pull on the latter, a brake for the said device, and a movable platform adjacent to the door and controlling the circuit for the said electric motor.

6. An automatic door opening and closing device, comprising an electric motor, a sprocket-wheel secured on the shaft of the motor, a sprocket-wheel carried by the door and connected by a sprocket-chain with the sprocket-wheel on the motor-shaft, a brake for the sprocket-wheel on the door, a movable platform under the door and extending on opposite faces thereof, springs on which the platform is mounted, suitable contact-plates in the said platform moving with the same, and fixed contact-plates adapted to be engaged by the said platform contact-plates, the electric circuit-wires of the motor being connected with the said platform contact-plates and the said fixed contact-plates.

7. An automatic door opening and closing device, comprising a slidable door, an overhead hanger for the door having ball-bearings, a motor at one side of the door, sprocket-wheels, one on the motor-shaft and the other on the door, a sprocket-chain connecting the sprocket-wheels with each other, a brake for the sprocket-wheel on the door, and a movable platform under the door and controlling the starting and stopping mechanism of the motor.

8. An automatic door opening and closing device, comprising a motor, a rotatable device on the door, means connecting the motor and said device for exerting a pull on the latter to move the door in one direction, means for preventing the device from turning when the door is moving in said direction, means for controlling the starting and stopping mechanism of the motor, and means for moving the door in an opposite direction.

In testimony whereof I have signed my name to this specification in the presence of two subscribing witnesses.

CLEOPHAS GAMACHE.
